FREIGHT BRACING DEVICE

William F. Eisensmith, Penns Grove, N.J.

Application March 26, 1946, Serial No. 657,212

9 Claims. (Cl. 105—369)

1

This invention has general reference to load braces or means and, more particularly, those of the species in the form of a barrier serviceable to prevent accidental shifting of stacked freight and the like during transit, or incidental to shunting of a car, truck, or other means for transportation from one loading location to another.

The primary aim of this invention is the provision of an improved form of bracing barrier, of the above indicated type including novel holding units which are equally applicable to temporary bulkheads, gates, and analogous means useful in box-cars, trucks and similar vehicles, which can be installed without the use of nails, cleats, or other conventional retention means.

Another aim of this invention is the provision of an improved brace-holder or unit, of the species indicated in the preceding paragraph, for attachment to partitions, barriers or gates, for holding stacked cargo and freight in place, with positive assurance such partition, barrier or gate will be rigidly retained in service position against movement in any direction.

A further aim of this invention is the provision of an improved brace unit which embodies novel means effective to positively resist transportation shocks imparted from the load end and which will firmly hold the load against shifting due to shocks coming from the opposite or rear end, or otherwise, thereof.

A still further aim of this invention is to provide an improved bracing unit including a reciprocatory, wall, floor, roof, or analogous, surface biting element which is capable of equally effective service irrespective of the active direction in which the unit be attached to a partition, barrier or gate; and without unduly marring the surface of the wall, etc., with which it coacts when installed in service position.

Still another aim of this invention is the provision of an improved bracing unit comprising but two main working parts that are easy to manufacture and which are of durable construction, whereby the cost of replacements is reduced to a minimum, while the wall or other surface biting element or elements are easily slid out of active position and held against movement when the attached partition, barrier or gate, is not in use.

While the foregoing definitions are indicative in a general way of the aims of this invention, other objects with ancillary advantages will be evident to those skilled in the art upon a full understanding of the construction, arrangement

2

and operation of the means hereinafter fully disclosed, but it will also be appreciated that said invention is susceptible of other embodiments and applications as well as structurally modified forms, than the one chosen for illustration, and all of which come equally well within the terms and scope of the concluding claims.

In the accompanying sheet of drawings:

Fig. 1 is a transverse section of a box-car body showing the application of the improved load bracing units, of this invention, to a freight retention gate, with the latter in active position.

Fig. 3 is a larger scale fragmentary elevation of one of the brace units in active position.

Fig. 3 is a section taken on the plane designated by the angled-arrows III—III in Fig. 2.

Fig. 4 is a still larger scale fragmentary view of the right hand portion of Fig. 3; and,

Fig. 5 is a fragmentary perspective view of the toothed or penetrating end of the gate holder hereinafter fully described.

In describing the form of this invention exemplified by the sheet of drawings herewith, specific terms will be employed for the sake of clarity, but it is to be understood the scope of said invention is not thereby limited; each such term being intended to embrace all equivalents which perform the same function for an analogous purpose.

30 Referring first to Fig. 1, more particularly, which depicts a cross-section of a typical freight or box-car including a bottom or floor 6, opposed sheet metal side outer walls 7 with wood lining 8, and a roof 9; while boxed or stacked cases of barrels and merchandise are designated by the reference character 10, whereas 11 indicates sealed containers.

A load protecting bulkhead, partition, or gate is comprehensively designated by the reference 40 numeral 12 the same consisting of spaced horizontal members 13 with end members 14 and a medially-located vertical member 14 that are rigidly connected together in rectangular formation, for example, by suitable securing means 15, 45 in an obvious manner. It is to be noted that the end portions of the gate 12 are reinforced by proximately-spaced inwardly-located additional vertical members 16 which serve to provide, with the end members 14, substantial and rigid support for the improved bracing devices or units 17, of this invention.

Each bracing unit 17, as best understood from Figs. 2 and 3, comprises a channel-section shell or keeper 18 of a length to span the adjoining gate members 14, 16, the web portion 19 of such

keeper being provided with a medial slot 20 having the outer end expanded in the form of a rectangular cut-out 21, for a purpose later explained; while the paralleling sides of the keeper 18 are, in part, outwardly angled to provide coplanar flanges 22 whereby said keeper is rigidly attachable to the members 14, 16, as by through bolts 23. Preferably, and as best understood from Fig. 3 the web portion 19 is inwardly inclined relative to the plane of the gate 12; or in other words the outer end of the keeper 18 is further away from said gate than at its inner end. Attention is also directed to the fact that the over-all width across the keeper flanges 22 corresponds with the spacial dimension intervening the gate members 13 so that the keeper 17 is firmly buttressed against planarly-related shifting in all directions.

Movably fitting the hollow or wedge-shaped channel 24 of the keeper 17 is a longitudinally grooved slide or oblong holder 25; said holder embodying a web portion 26 having approximately rectangular-section ribs 27 along its major sides to define an intervening groove, and a medially-lengthwise slot 28; as well as a T-section manipulator knob the head portion 29 whereof is of a size for passage through the keeper cut-out 21, while the rectangular-section shank 30 is freely slideable along the slot 28 in said keeper 18, as later explained.

For maintenance of the keeper 18 and holder 21 in cooperative relation use is made of a screw-stud 31, preferably having a rectangular head 32 for slideable movement along the groove defined by and intervening the spaced ribs 27 of the holder 25, while the threaded-shank portion of said stud is fitted with a wing-nut 33 for clamping engagement against a pad 34 on the outer face of the keeper 18, all as readily understood by those conversant with the art.

Particular attention is directed, at this juncture to the fact that the holder ribs 27 are extended outwardly beyond the beveled blade-like end 35 of the holder 21 to provide spaced penetrating teeth 36, preferably of substantially triangular cross-section to enable easy embedment in the wood lining 8, such teeth preferably having the outer and upper faces 37, 38 respectively flat; whereas the inner face 40 is curvilinearly chamfered down to a knife edge 39 as shown to best advantage in Fig. 5, but likewise clearly understandable on an examination of Figs. 2 to 4. It will now be clearly seen that the holder 25 and its teeth 36 as well as the blade-like end part 35 respectively penetrate and snub the car lining 8 at an angle countering the direction of load shocks, which feature is highly important since it results in positive resistance without appreciable damage to said lining while at the same time holding the freight 10, 11 against shifting.

Having outlined the structural features of my improved bracing device or unit 17 it will be readily understood that four such units are conveniently attached by through bolts 23 immediately above, and similarly below, the lowermost and uppermost horizontals 13 of the gate 12, see Fig. 1; whereas the length of said gate is such as to ensure clearance at each end when placed intermediate the lining walls 8 of a conventional truck-body or box-car. Now it will be clearly appreciated that by provision of the slideable holder 25 in the bracing unit 17 of this invention that the gate 12 can be effectively used in trucks or box-cars of greater width; or, in other words, in trucks or box-cars of maximum width permit-

ted by railroad and other transportation regulations, incident to the outward extensibility of said holders 25. It will also be appreciated that prior to placing the gate 12 in position against the freight 10, 11, for example, that the holders 25 will have been previously retracted, or moved out of harmful projection, within the respectively associated units 17 and so retained by tightening-up the wing-nuts 33. This feature of reTRACTABILITY of the holders 25 is also highly advantageous in that it ensures protection for the teeth 36 against injury, or being the cause of damage, when the gate 12 is not in use or stored away. After the gate 12 has been applied against the

freight 10, 11 all that is necessary to do is to consecutively release the wing-nuts 33 and to slide the holder 25, by aid of the manipulator head or knob 29, outwards until the teeth 36 impact the confronting wood-lining 8, when by a few blows against the inner side of said knob, with a hammer or other appropriate article, the teeth 36 can be readily driven into penetrative engagement with the lining 8 or until the beveled edge 35 also impinges the lining 8, whereupon the associated wing-nut 33 is tightened-up with resultant locking of the holder 25 in active position. Corresponding procedure is followed with each of the units 25 until the gate 12, as a whole, will be rigidly located in effective service position.

30 It is to be observed that the teeth 36, by virtue of their particular formation, enable easy imbedment thereof in the wood-lining 8 due to the sharp edges defined by the respective flat and relatively curved faces 37, 38 and 40 inclusive. 35 More specifically the curved faces 38, 40 materially assist penetration as well as prevent "scrapping" of the lining 8. When the truck or car receives transit shocks the flat faces 37, 38 positively resist any tendency to give under such 40 shocks, into which they have recessed, under all normal operating conditions. It is also noteworthy that when the blade-like edge of the beveled portion 35 of the slideable holder 25 impinges the lining 8 it does so with a snubber-like action, 45 due to its "K"-like angular engagement, with that of the teeth 36, whereby said holder 25 cannot move or become accidentally dislodged. This feature is further fortified by the location of the tooth flat face 37, counterwise, or in opposition, 50 to the beveled edge portion 35, whereby the rigid retaining capacity of the holder 25 is considerably enhanced; while it has been found in actual practice, with the parts 35 and 36 set-up as aforesaid, that it is practically impossible to move the teeth 55 36 under heavy shocks or excessive pressure. Another advantage inhering to this invention is that the teeth 36 and bevel 35, due to their particular formation and angle of penetration, have been found to result in but negligible damage to 60 the lining 8 inasmuch as, under general service shocking of the parts the brace unit 17, as a whole, is rigidly held in place; whereas the gate 12 can be easily installed or removed without any special teaching, or the necessity of using tools 65 other than a hammer or similar article. Still further under rigorous tests the unit 17 has proven its ability to withstand all normal transportation shocks, and to effectively hold in place, separate, or otherwise protect light, fragile, or perishable merchandise; just as well as preventing shifting of heavier grades of freight during transit.

From all the foregoing it will be understood that by the herein disclosed invention there is provided a readily set-up or removable barrier,

bulkhead partition, or gate, which fully answers all the objectives set forth in the prefatory paragraphs of this specification; while it is of a type equally effective in beam form, or otherwise as desired, inasmuch as it can be easily installed in various positions and directions other than the one described with corresponding advantages.

Having thus described my invention, I claim:

1. A load brace for freight transporting vehicles comprising a freight abutment member; opposingly-effective securing units rigidly attached to said member; each such unit including a keeper with a wedge-shaped passage therethrough and a holder slidably therein; spaced teeth at the outer end of the holder with an intervening bevel-edge respectively adapted to inclinedly-penetrate and impinge opposed wall faces of the vehicle counterwise to transit load shocks; means whereby the keeper and holder are maintained in co-operative assembly; and means whereby the holder may be held retracted within the keeper or arrested at differential extension relative to said keeper.

2. A load brace for freight transporting vehicles comprising an abutment partition composed of rigidly connected horizontal and vertical members; aligned opposedly-effective bracing units rigidly attached to said partition intermediate adjoining pairs of the horizontal and vertical members; each such unit including a keeper with a wedge-shaped groove therethrough; a holder member slidable in the groove of said keeper and having spaced teeth with an intervening bevel-edge at its outer end, said teeth and bevel-edge inclinedly-engaging opposed inner walls of the vehicle counterwise to transit load shocks; means whereby the keeper and toothed holder are retained in operative connection; and means effective to maintain the toothed holder retracted into the keeper, or to arrest said holder variably extended outwards relative to said keeper.

3. The combination of claim 2 wherein the abutment partition is in the form of a gate comprising rigidly connected spaced horizontal members, with end and a medially-located vertical members; wherein said gate is reinforced at the ends by relatively spaced inwardly-located additional vertical members; and wherein the partition securing units have overall dimensions, lengthwise and laterally, to span the end and relatively spaced vertical members, as well as to snugly fit between proximate horizontal members, whereby said units are buttressed against planar shifting with respect to the gate.

4. A securing device for freight braces comprising an inclined keeper with a wedge-shaped passage therethrough and including means for its attachment to the brace abutment member; a holder slidable in the passage through the keeper, said holder embodying wall-penetrative projections with an intervening inclined edge at its outer end; means maintaining the keeper and holder in operative connection and effective to enable relative extension; and means whereby the

holder may be arrested telescopically within the keeper, or firmly secured at differential relative extension.

5. The invention of claim 4 wherein the keeper
5 is in the form of a channel-section shallower at
one end than at the other and having the flange
portions, in part, outwardly angled to form co-
planar attachment means; and wherein the web
portion of said keeper is provided with a medial
10 slot having an enlargement at one end, for the
purpose specified.

15 6. The invention of claim 4 wherein the web portion of the keeper is provided with a medial slot having a rectangular enlargement at one end; wherein the holder is in the form of a longitudinally grooved slide having spaced wall-penetrative approximately-triangular section teeth with an intervening reversely effective bevel edge at its outer end; and wherein said holder embodies a manipulator knob engageable through the keeper medial slot.

25 7. The invention of claim 4 wherein the holder
is in the form of an oblong slide having approxi-
mately rectangular-section ribs along the major
sides thereof to define an intervening groove;
and wherein said ribs are extended outwardly
beyond the inclined edge of the slide to provide
wall-penetrative teeth; wherein the said teeth
have the outer and upper faces respectively flat;
30 and wherein the inner faces of said teeth are
chamfered down to define knife edges for the
purpose specified.

purpose specified.

8. The invention of claim 4 wherein the means maintaining the keeper and holder in operative connection consists of a T-section manipulator knob; wherein the head portion of such knob is of a size for outward passage through a complementally contoured cut-out in the keeper; and wherein the shank portion of said knob is of rectangular cross-section for slidable movement along a slot extending from the keeper cut-out aforesaid.

9. The invention of claim 4 wherein the means for arresting and securing the holder in telescoped or extended position relative to the keeper comprise a screw-stud having a suitably-shaped head for non-rotative engagement in a groove in the holder inner surface; and wherein said screw-stud is fitted with a wing-nut for rigid clamping coaction against the outer face of the keeper.
